TRANSVAAL.

ROCK-DRILLING MACHINE OR ENGINE.

No. 832,791.

Specification of Letters Patent.

Patented Oct. 9, 1906.

Application filed July 12, 1905. Serial No. 269,407.

To all whom it may concern:

Be it known that we, HENRY HELLMAN and LEWIS CONDICT BAYLES, citizens of the United States, residing at Johannesburg, Transvaal, have invented certain new and useful Improvements in or Relating to Rock-Drilling Machines or Engines, of which the following is a specification.

This invention relates to rock or like drilling machines or engines actuated by means of compressed air or other expansive gaseous fluid, and especially to providing a machine or engine of the type aforesaid with dust prevention or washing means for the drill or bit and for imparting intermittent rotation to said drill or bit.

We will at once proceed to describe our invention in detail by aid of the accompanying drawings, wherein—

Figure 1 illustrates the complete machine in longitudinal elevation. Fig. 2 represents it in longitudinal section. Fig. 3 is a transverse section on line $x-x$, Fig. 2. Fig. 4 is a transverse section on line $y-y$, Fig. 2. Fig. 5 is a transverse section on line $z-z$, Fig. 2. Fig. 6 is a transverse section on line $x'-x'$, Fig. 2. Fig. 7 is a transverse section on line $y'-y'$, Fig. 2. Fig. 8 is a transverse section on line $z'-z'$, Fig. 2. Fig. 9 is a transverse section on line $x'-y'$, Fig. 2. Fig. 10 is a transverse section on $y'-z'$, Fig. 2. Fig. 11 is a longitudinal section of the front portion of the machine, showing a slight modification. Fig. 12 is a view of the cylindrical piece 33, which is screwed into the cylinder-cover 29; and Fig. 13 is a view of the tubular piece 39, which surrounds said cylindrical piece 33 and constitutes the means whereby the intermittent rotary motion is transmitted to the power-cylinder and drill or bit.

In the drawings 1 designates an outer cylindrical protective casing in which the power-cylinder 2 is slidingly and rotatively mounted.

The casing 1 is shown carried or supported by means of a sleeve or clamp 3, constructed with a cone 4 for fixing it to an ordinary column-clamp or other suitable support. The sleeve or band 3 is shown severed or split, one of the ends being constructed with a bifurcation or with the two projections 5 6 and the other with a projection 7, fitting into said bifurcation. The ends of the part 7 and the two parts 5 6 are turned up in the form of

hooks, and between them is inserted a tapered key 8, which when driven in one direction forces the part 7 into the bifurcation formed between the parts 5 6, and so securely binds the sleeve or band 3 round the protective casing 1. The casing 1 may be adjusted longitudinally of the band or sleeve 3 in either direction, as may be desired, to advance or recede the machine in relation to the rock face or point at which it is desired to operate upon.

The protecting-casing 1 at the forward end is constructed of approximately the same internal diameter as the external diameter of the power-cylinder 2, so that the power-cylinder is capable of sliding freely backward and forward through its bearing in this end of the casing 1. Instead of constructing the end of the casing 1 in the manner shown and described it will be evident that it may be fitted with a cap or bush screwed over or into the protecting-casing 1 at the forward end to form the bearing for the power-cylinder 2.

In the bore of the power-cylinder 2 at the forward end is located an impact piece or cylinder 9, which serves to receive the impacts of the reciprocating percussive member 10 and to transmit the same to the inner extremity of the shank 11 of the drill-bit or boring-tool 12. The impact-piece 9 is capable of a limited movement in the front end of the cylinder 2. In the bore of the cylinder 2, in front of the impact-piece 9, is fitted a bush 13, which is formed with a square or polygonal bore. (See Fig. 10.) The shank 11 of the drill-bit or boring-tool 12 is made of corresponding square or polygonal section to fit the bush 13, so that the drill or bit is incapable of rotary motion inside the forward end of the power-cylinder 2.

In the arrangement illustrated in Fig. 2 for providing a supply of water or other liquid to the cutting extremity of the bill or bit 12 an annular groove or recess 14 is formed round the cylinder 2 at the forward end, and inside the cylinder 2, round the impact-piece 9, is formed an annular recess 15. The external annular recess 14 is placed in communication with the internal annular recess 15 by means of the two (more or less) ports or holes 16. In the external annular recess 14 in the cylinder 2 is located a swivel or swivel-piece 17, which is constructed in halves and bolted together through perforated lugs 18. This

swivel-piece 17 is constructed with an internal annular groove 19 and with a boss 20, into which is screwed a hose-stem 21. The hole 22 in the hose-stem is placed in communication with the annular recess 19 by means of a hole 23, formed in the swivel-piece 17 at the bottom of the recess 19.

24 is a flexible hose or other suitable pipe fixed round the lower end of the hose-stem 21 by the clamp 25 for conducting water (which is placed under pressure) to the swivel 17 and from the latter to the annular recess 15 in the cylinder 2.

In the impact-piece 9 are formed two 15 (more or less) angular ports 26, which are inclined in a forward direction and meet in a central hole 27, which opens at the front of the impact-piece 9. A hole 28 is formed longitudinally of the drill-steel, terminating at 20 the center of the cutting extremity of the bit 12 or in any other suitable position at or in close proximity to the end thereof, from which the water may issue to prevent the formation of dust by the repeated impacts of 25 the drill or bit 12 upon the rock. The annular recess 15 in the cylinder 2 is made sufficiently long for the ports 26 in the impact-piece 9 to remain in communication with said recess 15 should the impact-piece 9 be moved 30 forward in the cylinder 2, owing to the bit or drill 12 not coming into contact with the rock.

In the power-cylinder 2, is arranged the piston 10, which constitutes the reciprocating percussive member. This piston 10 operates to control the admission of the actuating 35 fluid to impel it on its forward and percussive and rearward and idle strokes inside the cylinder 2.

To the rear end of the power-cylinder 2, inside the casing 1, is screwed the cylinder-cover 29. This cover 29 is formed with an external annular groove 30, in which are located a packing 31 and beneath the packing 31 a spring 32, which spring keeps the packing 31 45 tightly pressed against the internal walls of the protective casing 1. This packing 31 prevents the passage past it of the actuating fluid and by confining the actuating fluid to the rear of the cylinder-cover 29 utilizes the 50 expansive force of said fluid to feed the drill 12 or to force the power-cylinder 2 forward in the protecting-casing 1 to keep the drilling or boring bit 12 in contact with the rock or bottom of the hole in which it is operating. The 55 cylinder-cover 29 serves as the piston upon which the actuating fluid exerts its pressure to feed the drill.

Into the cylinder-cover 29 is screwed a cylindrical piece 33. (See Figs. 2 and 12.) 60 This piece 33 is constructed with a collar or annular projection 34, and in the circumference of the annular projection 34 are formed a number of curved tapering peripheral grooves 35. (See Figs. 6 and 12.) In an annular recess formed between the front of the

collar 34 and the rear of the cylinder-cover 29 is placed a cylindrical swivel-piece 36, which is made of approximately the same internal diameter as the diameter of the collar 34. Inside the curved tapering grooves 35 in the collar 34 are fitted balls 37, which allow the cylindrical piece 33 to rotate inside the swivel-piece 36 when said balls 37 take up a position in the larger ends of said grooves 35. The cylindrical piece 33 at its rear end is constructed with a longitudinal slot 38.

Over the rear end of the cylindrical piece 33 is arranged a tubular piece 39, which is constructed with a flange or annular enlargement at its forward end which abuts the rear end of the collar 34 on the cylindrical piece 33. In the periphery of the flange of the tubular piece 39 are formed curved tapering peripheral grooves 40, similar to the grooves 35 in the collar 34, and in these grooves 40 are 85 located balls 41, which serve to prevent the rotation of said tubular piece 39 in one direction inside the cylindrical swivel-piece 36, while permitting it to be rotated in the reverse direction. In the tubular piece 39 are 90 formed two opposing spiral slots 42. (See Fig. 13.) In the cylindrical swivel-piece 36 at the rear of the flange of the tubular piece 39 is located a rotation washer or ring 43, which serves as a bearing for the tubular 95 piece 39. Said rotation-washer 43, being seated in a recess inside the cylindrical swivel-piece 36, serves for keeping the tubular piece 39 in its correct position inside the swivel-piece 36. 100

In the rear end of the cylindrical swivel-piece 36 is screwed or otherwise suitably secured a rear cylinder 44, made of square or other suitable polygonal external sections. The inner end of this cylinder 44 abuts the 105 rear of the rotation-washer 43 and so retains it in position in the recess in the cylindrical swivel-piece 36.

On the end of the protective casing 1 is 110 secured the casing-cap 45, which is constructed with a hole 46, tapped to receive the throttle-valve of the actuating-fluid-supply pipe. In this inlet 46 is fitted a ring 47, which carries a gauze strainer 48, through which the actuating fluid must 115 pass in its passage to the machine. This strainer 48 serves for removing any particles of solid matter that may be contained in or carried by the actuating fluid before it passes into the interior of the machine.

49 is a port formed in the casing-cap 45, which places the actuating-fluid inlet 46 in communication with the rear end of the protecting-casing 1 and at the rear of the packing 31, located around the cylinder-cover 29. 120

The casing-cap 45 is shaped internally to fit the rear cylinder 44, and in the end of said cap 45 is located a cup-leather 50, and at the rear of the cup-leather 50 a metal ring 51, over which is screwed a nut or cap 52, which 130

serves to keep the ring 51 and cup-leather 50 in position on the rear end of the casing-cap 45. By means of the cup-leather 50 a fluid-tight sliding joint is made between the exterior of the rear cylinder 44 and the interior of the casing-cap 45, thereby preventing any escape of the actuating fluid between the rear cylinder 44 and said cap 45. The polygonal external shape of the cylinder 44 and 10 the corresponding shape of the casing-cap 45 prevents the rotation of the rear cylinder 44.

In the cylinder-cover 29 and communicating with the protecting-casing 1 at the rear of the packing 31 is a port 53, which constitutes the main supply-port to the power-cylinder 2. This port 53 communicates with an annular recess 54, formed in the face of the cylinder-cover 29 next the cylinder 2. A port 55, formed longitudinally of the 20 power-cylinder 2, communicates at one end with the annular recess 54 in the cylinder-cover 29 and at the other end communicates with the power-cylinder 2. This port 55 constitutes a continuation of the main supply-port 53 to said power-cylinder 2.

The power-piston 10 is, as shown, constructed of two different external diameters or formed with a rear portion 56 of larger diameter than the front portion 57. The 30 piston 10 is bored out axially for the greater portion of its length, this bore 58 opening to the interior of the cylinder 2 at the rear end of the piston 10. A port 59 is formed in the piston 10, communicating with the axial bore 58 at its inner end. In the bore 60 of the power-cylinder 2 (which is formed of two different internal diameters corresponding to the piston 10) and at the forward end is formed an annular recess 61, and through 35 the cylinder 2 are formed several radial ports 62, communicating at their inner ends with the annular recess 61 and at their outer ends through the ports or grooves 63 with the annular space formed between the protecting-casing 1 and the power-cylinder 2. These 40 grooves 63 are made somewhat longer than the length of the bearing afforded for the power-cylinder 2 in the front end of the protecting-casing 1, so that when the ports 62 45 (which constitute the exhaust-ports) are in the center of the bearing in the forward end of the protecting-casing 1 said grooves 63 open to the interior of the casing 1 and also to the exterior beyond said bearing. As the 50 power-cylinder 2 advances in the protecting-casing 1 from such position the grooves 63 close to the interior of the casing 1, but open more fully to the atmosphere until finally the 55 ports 62 are clear of the bearing in the front 60 end of the protective casing 1. Thus an unrestricted exit is always provided for the exhaust.

64 represents exhaust-ports formed at the forward end of the protective casing 1, while 65 65 represents ports (which serve also as ex-

haust-ports) provided for a special purpose to be hereinafter explained.

The action of the piston 10 and the manner in which it controls the admission of the actuating fluid to the power-cylinder 2 to 70 impel the piston 10 on its forward and percussive and rearward and idle strokes may be described as follows: In the position in which the piston 10 is shown in Fig. 2 it is traveling in a rearward direction and has 75 almost completed its rearward stroke. In this position the actuating fluid is admitted to the front end of the enlarged portion 56 of the piston 10 and acting on the annular surface 66 is impelling it through its rearward 80 stroke. Immediately before the piston 10 reaches the end of its rearward stroke, and aided by the momentum it acquires in performing said rearward stroke, the ports 59 in the piston 10 which communicate with the 85 inner end of the bore 58 run into the larger bore 60 of the power-cylinder 2, whereupon the air or fluid at the initial pressure, passing through said ports 59 to the rear of the piston 10, impels it on its forward and percussive 90 stroke. Simultaneously, or approximately simultaneously, with the impact of the forward end of the piston 10 on the impact-piece 9 the ports 59 open into or communicate with the annular recess 61 in the 95 power-cylinder 2, which permits the actuating fluid to pass from the rear end of the piston 10 and to escape through the exhaust-ports 62 64 to the open. When the rear end of the piston 10 is in communication with exhaust, the air at initial pressure, passing out of the supply-port 55 in front of the head 56 of the piston 10, again impels it on its rearward or return stroke. This cycle of operations is repeated for each outward and return 100 stroke of the power-piston 10. In the rear cylinder 44 is located a somewhat similarly constructed and operated piston 67. This rear cylinder 44 is also constructed of two different internal diameters, the front portion corresponding to the larger diameter of the piston 67 and the rear portion to the smaller diameter thereof. The bore of the piston 67 is made larger at the front end, and into it project the cylindrical slotted piece 115 33 and the tubular slotted piece 39. Secured transversely of the piston 67 is a pin 68, which projects through the curved or spiral slots 42 in the tubular piece 39 and also through the longitudinal slot 38 in the cylindrical piece 33.

Longitudinally of the cylindrical swivel-piece 36 and communicating at its forward end with the interior of the protecting-casing 1 is formed a port 69, and longitudinally of the rear cylinder 44 is formed a port 70, which coincides with the port 69. This port 70 communicates with the interior of the rear cylinder 44 at the rear end of the larger bore. In the smaller bore of the rear cylinder 44 is 130

formed an annular recess 71, which communicates with an exhaust-port 72, opening to the rear of the machine. The piston 67 is constructed with a transverse port 73, which 5 serves for alternately admitting the actuating fluid to the interior of the cylinder 44 and for exhausting it therefrom. This piston 67 operates in a somewhat similar manner to the power-piston 10—that is to say, the actuating fluid at initial pressure is free to flow along the ports 69 70 in the cylindrical swivel-piece 36 and rear cylinder 44, respectively, and to enter the larger bore of the rear cylinder 44 at the back of the larger front portion 10 of the piston 67. Assuming the piston 67, as seen in Fig. 2, to be traveling in a forward direction, then the force of the actuating fluid being exerted on the rear end of the enlarged part is impelling it on its forward stroke. 15 Just before the piston 67 reaches the end of its stroke in a forward direction the port 73 in the piston 67 runs into the larger bore of the cylinder 44 and so admits the actuating fluid to the interior of the piston 67, whereupon it is moved through its rearward stroke until said port 73 communicates with the recess 71 and places the interior of the piston 67 in communication with the exhaust-port 72. The actuating fluid then acting on the 20 annular surface of the enlarged front part of the piston 67 again traverses it through its forward stroke until the port 73 again runs into the enlarged bore of the cylinder 44, whereupon the above cycle is repeated. 25 To the outer end of the rear cylinder 44 is attached a handle 74, which serves for retracting the rear cylinder 44 and power-cylinder 2 in the protecting-casing 1. 30 The intermittent rotary motion in one direction is transmitted to the power-cylinder 2 and from the latter to the drill or bit 12 by means of the piston 67 in the rear cylinder 44. The mechanism may be arranged so as to impart this intermittent rotary motion to 35 the power-cylinder 2 either during the forward or rearward movement of said piston 67. Arranged as shown in the drawings it effects the intermittent rotary motion on the rearward stroke. It is accomplished in the following manner: The pin 68 on the piston 67, as previously explained, engages the two spiral slots 42 in the tubular piece 39 and the longitudinal slot 38 in the cylindrical piece 33. In the rearward movement of the piston 40 67 the balls 41 take up such a position in the curved peripheral grooves 40 in the flange of the tubular piece as to prevent rotation of said tubular piece 39. The tubular piece 39 is by this means held stationary inside the piece 36, which, being attached to the rear cylinder 44 and made of polygonal external section, is incapable of rotary motion. When the piston 67 moves through its rearward stroke and the tubular piece 39 is stationary, 45 the pin 68, engaging the spiral grooves 42, is

constrained to traverse the spiral slots 42, which imparts rotary motion to the piston 67 and through the medium of the pin 68 simultaneously rotates the cylindrical piece 33, the balls 37 in the periphery of which take up 50 a position in the larger ends of the peripheral grooves 35 and so permit it to rotate. This latter piece 33, being attached to the cylinder-cap 29 and through the latter to the cylinder 2, transmits the rotary motion to the cylinder 2 and through the latter to the drilling or boring bit or tool 12. In the forward movement of the piston 67 the balls 41 in the peripheral grooves 40 in the tubular piece 39 take up a 55 position in the larger ends of said peripheral grooves 40 and so allow said tubular piece 39 to rotate while the piston 67 moves in a rectilinear path, guided by the pin 68 in the slot 38 in the cylindrical piece 33, and thus no rotary motion is imparted to the cylinder 2 on 60 the forward stroke.

In the operation of the machine the actuating fluid is admitted through the inlet 46 and after passing through the strainer 48 enters the rear end of the protective casing 1 at 65 the back of the packing 31 in the power-cylinder cover 29. The feeding of the drill, as previously explained, is effected by the actuating fluid exerting pressure on the cylinder-cap 29 and moving it forward in the protective casing 1. The actuating fluid enters the port 53 in the cylinder-cap 29 and actuates the power-piston 2 in the manner previously explained, and the fluid also passes from the rear end of the casing 1 along the ports 69 70 to the rotation-piston 67 and actuates the 70 rotary gear, as before described. Thus the feed and rotation of the machine are automatically effected. The water-supply is turned on and shut off as required in the 75 working of the machine for the purpose of preventing the formation of dust and for washing away the cuttings from the cutting end of the drill or bit 12. When the power-cylinder 2 has advanced sufficiently far in the 80 protecting-casing 1 for the packing 31 to overrun the port 65 in the protective casing, then the actuating fluid by escaping through 85 said ports 65 puts the machine out of operation and indicates to the operator that it requires to be retracted and the drill or bit 90 replaced by a longer one.

In Fig. 11 we illustrate a slight modification in the arrangement at the forward end of the power-cylinder 2. In this case the impact-piece 9 as a separate member is dispensed with, and the shank 11 of the drill or bit 12 is shaped to itself project into that part of the bore of the power-cylinder 2 in which the piston 10 reciprocates, so that it 95 receives directly upon its inner end the impacts of said piston 10. The bore of the power-cylinder 2 at the forward end is made tapering for some distance and then reduced and made parallel to the forward end of that 100

part of the bore in which the piston 10 reciprocates. In the tapered hole is fitted a bush 13^a, which is made with a parallel bore to fit the part 11 of the drill-shank. 11^a is an annular projection formed on the shank 11, which abuts the bush 13^a and front end of the power-cylinder 2 when it is in position. The inner part 11^b of the shank 11 projects slightly into the bore of the cylinder 2, and the shoulder 11^c, formed between the parts 11 11^b, abuts the bottom of the tapered hole. The drill-steel 12 is constructed with the longitudinal hole 28 and with the two angularly and forwardly inclined holes 26^a communicating therewith. The head or forward end of the cylinder 2 is also constructed with the internal annular recess 15 and with the radial ports 16, placing said annular recess 15 in communication with a recess 14, formed round the cylinder 2. In this latter recess 14 is located the swivel 17, formed with the internal annular recess 19 in communication with the ports 16, annular recess 15, angular holes 26^a, and longitudinal hole 28. 21 represents the stem, 24 the hose-pipe, and 25 the hose-clamp, which serve for conducting water or other liquid to the swivel 17, from which it passes to the longitudinal hole 28 in the drill-steel 12 to the cutting-face thereof.

30 What we claim as our invention, and desire to protect by Letters Patent, is—

1. In a rock-drilling machine or engine, a rotatable power-cylinder having a side port at its forward end, a drill-steel slidably and non-rotatably held at said forward end of the power-cylinder, and having a passage extending longitudinally of said steel and communicating with the side port aforesaid, and a liquid-supply swivel loosely surrounding the forward end of the power-cylinder and having a port in communication with the side port aforesaid.
- 40 2. In a rock-drilling machine or engine, a

rotatable power-cylinder, having a side port at its forward end, a drill-steel slidably and 45 non-rotatably held at said forward end of the power-cylinder, and having a passage extending longitudinally of said steel, an impacting piece at the shank end of said steel and having an opening registering with the aforesaid 50 passage and also communicating with the side port aforesaid, and a liquid-supply swivel loosely surrounding the forward end of the power-cylinder and having a port in communication with the side port aforesaid. 55

3. In a rock-drilling machine or engine, a rotatable power-cylinder, having a side port at its forward end, a drill-steel slidably and non-rotatably held at said forward end of the power-cylinder, and having a passage extending 60 longitudinally of said steel, means carried by the power-cylinder for imparting intermittent rotation thereto, and means for supplying fluid to the side port in said cylinder during its rotation. 65

4. In a rock-drilling machine or engine, a rotatable power-cylinder having an annular recess upon the exterior of the cylinder at its forward end and a port through said cylinder at said recess, a drill-steel slidably and non-rotatably held at said forward end of the power-cylinder and having a passage extending longitudinally of said steel and communicating with the side port aforesaid, and a 70 liquid-supply swivel loosely fitting within the 75 recess aforesaid and having an internal annular chamber in communication with the side port aforesaid.

In witness whereof we have hereunto set our hands in the presence of two subscribing 80 witnesses.
